CLAIM

The ornamental design for a golf club head, as shown and described.

DESCRIPTION

FIG. 1 is a top plan view of a golf club head embodying the inventive design.

FIG. 2 is bottom plan view thereof.

FIG. 3 is a front elevational view thereof.

FIG. 4 is a rear elevational view thereof.

FIG. 5 is a heel-side elevational view thereof.

FIG. 6 is a toe-side elevational view thereof.

FIG. 7 is a top rear perspective view thereof; and,

FIG. 8 is a top front perspective view thereof.

The broken lines immediately adjacent the shaded areas represent the bounds of the claimed design, while all other broken lines are directed to environment and are for illustrative purposes only; the broken lines form no part of the claimed design.
